METHOD AND APPARATUS FOR FILTERING LIQUID IN A CLOTHES WASHING MACHINE
Anthony Mason, Benton Harbor, Mich., assignor to Whirlpool Corporation, Benton Harbor, Mich., a corporation of Delaware

Filed May 1, 1964, Ser. No. 364,090
12 Claims. (Cl. 8—158)

The present invention relates to home appliances and more particularly concerns improvements in filtering apparatus for laundry machines.

In the course of a washing cycle in a washing machine, washing or rinsing fluid drawn from the bottom of the tub or pool may be returned thereto. In order to avoid return of lint and other entrained foreign material with the recycled water, it is desirable to have a filter somewhere ahead of discharge of the returned water into the pool or tub. From time-to-time the filtering device must be cleaned to remove the lint and foreign material filtered out of the water.

An important object of the present invention is to provide a new and improved filter structure for laundry machines which is of simple and inexpensive construction comprising a small number of rugged, long lasting parts, and which may be installed and removed for cleaning conveniently and easily.

Another object of the invention is to provide a new and improved filter apparatus which is especially suitable for domestic washing machines of the wringer type.

A further object of the invention is to provide a novel filtering apparatus which can be installed directly in the washing pool or tub of a domestic washing machine of the agitator type.

Still another object of the invention is to provide a new and improved filtering unit which is of unusually large capacity in a small unit.

Other objects, features and advantages of the present invention will be readily apparent from the following detailed description of a preferred embodiment thereof taken in conjunction with the accompanying drawings, in which:

FIGURE 1 is a fragmentary plan view, partially in section, disclosing features of the invention;

FIGURE 2 is a vertical sectional elevational view taken substantially on the irregular section line II—II of FIGURE 1;

FIGURE 3 is a front elevational view of the filter device alone;

FIGURE 4 is a vertical sectional elevational view taken substantially on the line IV—IV of FIGURE 3; and

FIGURE 5 is a horizontal sectional detail view taken substantially on the line V—V of FIGURE 3.

While the principles of the present invention as embodied in a filter unit 7 may be useful in other environments, an especially useful application of such principles is demonstrated in a domestic laundry appliance such as a clothes washing machine 8 of the well-known oscillatory agitator type and including a stationary tub 9 of suitable size within which a load of clothes, wash water and detergent are agitated during a washing period. For efficiency and economy, recirculation of the washing water for different and successive loads of wash is desirably effected through a recirculation conduit 10 by means of the usual pump (not shown). Suitably the recirculation conduit 10 may be mounted by means of a bracket structure 11 on and alongside the usual wringer drive shroud 12. Entry of the recirculation conduit 10 into the tub 9 is effected by means of an upper gooseneck or inverted U-shaped portion 13 extending through a suitable opening 14 provided for this purpose in the

2

upper part of the tub well above the water line and having its edge protectively encased in a suitable rubber grommet 15. Access into the tub 9 from the top is through the usual top opening desirably closed by a removable cover 17.

According to the present invention, the filter unit 7 is constructed and arranged to be removably mounted within the tub 9 at a suitable location to be detachably connected to the recirculation water conduit gooseneck 13 and to be substantially submerged in the wash water. To this end, the filter unit includes as the major component a generally flattened, upwardly opening pocket-like receptacle 18 having a front wall 19 and a rear wall 20 which are desirably generally parallel vertically but are of opposite bowed arcuate shape horizontally and merge at their sides whereby to afford a generally lanceolate cross-section. A bottom wall 21 joins the lower ends of the walls 19 and 20 and provides therewith a receptacle of substantial volume elongated horizontally and opening at the top. Reinforcement for the upper end of the front wall 19 is afforded by a forwardly directed integral flange 22 which also serves as a convenient handle for manipulating the filter unit receptacle.

For removably mounting the receptacle 18, the bulging arch of the rear wall 20 is preferably formed complementary to the arc of the inside diameter of the vertical wall of the tub 9, and means are provided on the rear wall for supported interengagement thereof with a mounting block bracket 23 carried by the tub wall. This bracket 23 may be formed as a die casting or molded rigid plastic member and carries or is engageable with the head of a securing screw 24 the shank of which extends rearwardly through a complementary hole 25 in the tub wall and is secured as by means of a nut 27 by which the head of the screw is tightly drawn up to secure the filter-supporting bracket 23 firmly in place.

To facilitate quick and easy mounting and removal of the filter receptacle 18 with respect to the supporting bracket 23, and to assure positive retention of the receptacle and firm engagement of the back wall 20 thereof against the tub wall, the bracket 23 is constructed of generally truncated wedge-shape, with its narrow end extending upwardly, and the back wall 20 is provided with a complementary rearwardly opening bracket socket 28 as best seen in FIGURES 2, 3 and 5. A dovetail formation of the upwardly tapering sides of the bracket 23 and complementary undercut groove formation of the opposite side walls 29 defining the socket 28 effects a satisfactory interengagement of the receptacle with the retaining bracket. To bias the receptacle toward the wall of the tub 9, the bracket 23 is constructed thickest at its upper end and with its front wall tapering rearwardly from the top down, and the walls defining the socket 28 are of complementary shape. Through this arrangement, mounting of the filter receptacle 18 is readily effected by moving it downwardly to engage the supporting bracket 23 in the socket 28.

In order to hold the receptacle 18 in its mounted position against upward displacement by the force of water and wash load as driven by the agitator of the machine, a suitable quick releasable latch 30 is provided. A desirable form of this latch comprises an upwardly projecting resiliently flexible latch lever 31 having on its lower end a forwardly opening generally U-shaped engagement base 32 engaging a rearwardly extending attachment flange 33 on the upper end of the bracket 23. Overlying the latch supporting flange 33 in spaced relation in the assembly is a keeper flange 34 which closes the top of the socket 28 in the rear wall 20 of the receptacle and serves as reinforcement. A clearance opening 35 in the front portion of the reinforcing and keeper flange 34 and the adjacent juncture of the front wall defining the pocket 28

clears the latch lever 31 therethrough and enables a latch dog 37 to engage upon the keeper flange 34 and thus retain the receptacle 18 against unintentional upward displacement.

Suitably, the latch arm 31 may be made from non-corroding metal, but in the form shown comprises a semi-rigid resilient plastic material of which polypropylene is quite satisfactory. Above the latch dog 37 an upwardly and forwardly inclined latch handle extension flange 38 on the latch lever provides a lead-in cam head engageable with a cam edge 39 defining the rear of the latch opening 35 during assembly of the receptacle 18 with the supporting bracket 23. Thus, during the assembly movement of the receptacle into position, the cam head flange 38 is engaged by the cam edge 39 and the latch lever 31 flexed forwardly to clear the latch dog 37 past the edge 39, until full downward assembly of the receptacle 18 on the bracket 23 has been effected whereupon the latch dog 37 snaps into latching engagement over the keeper flange 34. To release the receptacle 18, forwardly directed manual pressure against the lever arm handle portion 38 flexes the latch lever 31 forwardly to clear the latch dog 37 from the keeper flange 34 and the receptacle 18 can then be lifted upwardly away from the supporting bracket 23, the reinforcing handle flange 22 serving as a convenient hand hold for this purpose.

Recirculation water fed into the receptacle 18 from the conduit 10 passes from the substantial pocket chamber within the receptacle through a large area discharge opening 40 in the front wall 19. A filter screen 41 extends entirely across the discharge opening and in a desirable form comprises a 36-mesh stainless steel screen wire suitable for domestic washing machine use. Where, as in the illustrated instance, the receptacle 18 is made of a suitable plastic material such as polypropylene, the screen 41 may be mounted with its margins directly embedded and locked in the material of the front wall 19 about the opening 40 which is desirably defined thereabout by a reinforcing rib 42. At the top of the opening the rib 42 may desirably be extended to the side margins of the front wall 19 to assist in stiffening the front wall against collapsing rearwardly under the agitated load within the tub 9 in service. As best observed in FIGURES 2 and 3, the opening 40 is elongated horizontally and has its lower edge located substantially higher than the bottom wall 21 so as to afford a substantial sump in the bottom of the receptacle 18 for receiving and collecting lint and other foreign matter filtered from the recirculated wash water by the screen 41.

As shown in FIGURE 2, the preferred position of the filter receptacle 18 in relation to predetermined water level W in the tub 9 is with the upper side of the discharge opening 40 adjacent to and desirably below the water level. Thereby, slinging turbulence force of the agitator motivated water in the tub 9 provides a back-flushing action on the screen 41, as indicated by directional arrows, to dislodge lint or other foreign material from the screen for deposit in the sump area of the receptacle. Further, any tendency for turbulently moving wash to escape into the receptacle 18 or to get hung up thereon is avoided by the overhanging reinforcing and handle flange 22 which thus serves as a deflector lip.

During feeding of recirculation water into the receptacle 18 from the conduit 10, flow-blocking collection of lint and foreign matter on the inner side of the filter screen 41 is substantially prevented by maintaining a flushing circulation of the fed-in water across the screen. To this end, the water from the conduit 10 is fed through the gooseneck 13 into a vertical manifold 43 within one side of the receptacle chamber space defined by a vertical partition and the adjacent converging portions of the front and rear walls 19 and 20. At its lower end, the manifold is closed by the bottom wall 21. At its upper end, the manifold 43 is closed by a top closure flange 45 (FIGS. 1 and 4) having an upstanding nipple 47 of

5 an outside diameter to receive the discharge end of the gooseneck 13 thereabout, with an O-ring seal providing a water seal for the relatively low water pressure delivered by the recirculation water conduit. From the manifold 10 water under the relatively low but nevertheless substantial recirculation pump pressure discharge into the main portion of the filter receptacle chamber through a vertically elongated but limited length delivery orifice 49 (FIGURES 3, 4 and 5) provided between the front wall 19 and the adjacent edge of the manifold partition 44. By having the delivery orifice 49 aligned with the adjacent side of the delivery opening 40 and preferably adjacent the upper portion of such side, water discharging from the manifold 43 takes the form of a flaring stream which continuously flushes the inner face of the submerged filter screen 41 and thus tends to avoid the clogging of the screen 41 by lint and other foreign matter carried over in the recirculation water. The general flow pattern of the water thus delivered is indicated by directional arrows in FIGURES 3 and 5. As the force of the stream diminishes, especially in the side area of the receptacle chamber opposite from the manifold 43, the lint and foreign matter tends to settle out into the sump area in the bottom of the receptacle chamber formed by walls 18a and 18b. Thus, the submerged screen 41 is not only flushed continuously free from lint and other foreign matter by the transversely directed stream from the delivery orifice 49 during feeding in of the recirculation water, but during operation of the washing machine backflushing of the screen, as already described, assures dislodgment from the inner face of the screen of any lint or foreign matter that may collect thereon despite the transverse flushing delivery stream or which may collect thereon after the delivery pressure has been discontinued and ordinary drainage through the discharge opening 40 occurs. It may be observed in FIGURES 2 and 3, that the downwardly and rearwardly sloping wall defining the hanger bracket receiving socket 28 provides a downward deflecting surface facilitating diversion of backflushed lint and the like downwardly toward the sump area in the filter receptacle chamber.

In order to facilitate molding of the receptacle 18 from a suitable plastic material such as polypropylene to provide a semi-rigid, resilient receptacle frame, and to facilitate cleaning of the receptacle 18, the front and rear portions of the receptacle are preferably separably constructed as respective shells 18a and 18b. While these shells may be completely separable, a preferred construction comprises hinging the same such as by the provision of an integrally molded hinge 50 along the base portion of a parting 51. At the opposite sides the sections 18a and 18b have respectively thickened reinforcing frame margins 52 and 53 substantially abutting at the parting 51 (FIGURES 1, 3 and 5).

To serve as part of a pressure-responsive latch means to hold the shell sections 18a and 18b together separably, the manifold partition 44 is formed integrally with the rear section 18b and with its vertical edge adjacent to but spaced from the front wall 19. Vertically aligned, spaced grooved upper and lower gripping jaws 54 and 55 define between their ends and with the contiguous edge of the partition 44 a gap which affords the delivery orifice 49. Each of the gripping jaws 54 and 55 comprises a pair of opposed, stiffly resilient, bulbous cross-section gripping elements which are normally spaced apart slightly less than the thickness of the contiguous margin of the partition 44 so as to frictionally grip such margin firmly, but releasably, when pressed into engagement between the jaws. Through this arrangement, it is easy to open the receptacle 18 by pulling the jaws 54 and 55 free from the engaged margin of the partition 44 while swinging the sections 18a and 18b about the hinge 50. Closing of the sections 18a and 18b is easily effected by pressing them toward one another until the end margins 52 and 53 abut and the gripping jaws 54 and 55 retainingly

grasp the partition margin throughout their substantial lengths. By having the jaws 54 and 55 in engagement with the partition 44, any tendency toward separation of the receptacle sections 18a and 18b under the head of the water column in the manifold 43 is effectively resisted. Since recirculation water escapes with substantial freedom from within the receptacle 18 through the discharge opening 40, and when the tub 9 is filled the receptacle is substantially submerged, and pressures against the receptacle, if any, are toward the outside of the section 18a, tending to press it toward the section 18b which is in turn anchored on the bracket 23 and against the wall of the tub 9, assurance is had against unintentional opening of the receptacle along the parting 51.

To further provide a latching means to hold shell sections 18a and 18b together, end margins 52 is provided with hooked projections 52a that mate with recesses 53a in end margins 53, such as shown in FIGURE 5. The mating of hooked projections 52a with recesses 53a provides a semi-positive latching means for the frame margin. The frame margin can be readily separated by the operator by manually applying force that would cause the resilient hooked projections to yield from the latched position.

Strengthening of the partition 44 is effected by integral attachment to its upper end of the upper closure and nipple flange 45 which is conveniently constructed as an integral part of the rear wall 20 and the adjacent thickened side frame margin 53. Additional reinforcement and closure for the upper end of the manifold 43 is provided by a complementary flange portion 58 on the upper end of the front wall 19 overlappingly related to the adjacent portion of the nipple flange 45 and complementally engaging in the closed assembly of the sections 18a and 18b about the base of the nipple 47.

From the foregoing it will be apparent that the present invention has provided a substantially new and improved filter device especially suitable for use with domestic washing machines for filtering recirculation water. Such filtering device is constructed and arranged in convenient position within the washing machine tub, is readily removable for cleaning, is easily and quickly opened to be cleaned out and is easily and conveniently reassembled and remounted for service. In addition to other numerous features of novelty, the novel delivery of recirculation water with respect to the filter screen to provide a flushing stream thereacross affords substantial advantages. In addition, the submerged disposition of the screen permitting back-flushing of the same by force of agitator impelled wash water further increases the capacity of the filter receptacle without clogging of the screen. Since the filter screen is maintained free of clogging lint or other foreign material, internal pressure build-up within the filter receptacle is avoided, and simple squeeze pressure friction retaining means suffices to hold the separable, hinged sections of the receptacle together until deliberately pulled apart for cleaning of the receptacle.

Although minor modifications might be suggested by those versed in the art, it should be understood that I wish to embody within the scope of the patent warranted herein all such modifications as reasonably and properly come within the scope of my contribution to the art.

The embodiments of the invention in which an exclusive property or privilege is claimed are defined as follows:

1. A method of filtering liquid containing foreign matter liable to clog a filtration screen, delivering liquid containing the foreign matter into a receptacle having an opening through an upright wall and across which opening a filtering screen extends, and while continuing to deliver recirculation liquid into the receptacle directing a flushing stream of liquid generally horizontally across the inner face of the screen from one side of the opening and

5
into a chamber area of the receptacle beyond the opposite side of the opening, whereby as the flushing stream diminishes in velocity into said chamber space foreign material flushed from the screen tends to sink to the bottom of the receptacle.

2. Filtering apparatus adapted for use in a laundry machine having a tub for containing a laundry liquid and further including an agitator mechanism, comprising:

a filtering device comprising a receptacle including a back wall and a front wall, said back wall having means for attaching the same in filtering position,

said front wall having a screened discharge opening, said discharge opening being submerged in said liquid, means defining a delivery manifold on said receptacle communicating with the interior of the receptacle, and means for communication of a liquid delivering conduit with the manifold,

said manifold being located adjacent to one side of said opening and having a delivery orifice directed to drive a flushing stream of liquid from the manifold transversely across the inner surface of the screen.

3. A filtering device adapted for use in a laundry machine having a tub with a circular upright wall for containing a laundry liquid, comprising:

an upwardly opening receptacle of generally lanceolate horizontal cross-section providing a front section and a back section joined by a wall at the bottom affording a sump area within the receptacle, said back section being of a curvature substantially complementary to the curvature of the tub wall, means for removably attaching said back section contiguous the tub wall, means for delivering liquid to be filtered into the receptacle,

said front section having a discharge opening, said discharge opening submerged in said liquid, a filtering screen across said discharge opening, and the lower edge of the discharge opening being substantially above said bottom wall.

4. A filtering device adapted for use in a laundry machine having a tub with a circular upright wall for containing a laundry liquid, comprising:

an upwardly opening receptacle having a front section and a back section joined by a wall at the bottom affording a sump area within the receptacle, said back section, being of a curvature substantially complementary to the curvature of the tub wall, means for removably attaching said back section contiguous the tub wall, means for delivering liquid to be filtered into the receptacle,

said front section having a discharge opening, a filtering screen across said discharge opening, the lower edge of the discharge opening being substantially above said bottom wall,

said sections being separate along a parting extending through their meeting margins and along said bottom wall,

a hinge securing the bottom wall portions at each side of the parting, and means for separably retaining the sections together and enabling opening of the sections for cleaning out the sump area.

5. A filtering device as defined in claim 4, wherein said separable retaining means comprise frictional gripping means on one of said sections releasably engaging other of said sections.

6. A filtering device adapted to filter recirculation water in a laundry machine comprising a tub having a pool of turbulently agitated wash water and wash therein, said device including a receptacle having means for mounting it in partially submerged relation within the pool in the tub,

means for receiving recirculation water into the receptacle, the upper end of the receptacle being open and located above the pool of water and the lower end of the receptacle defining a foreign matter receiving sump therein, a front wall on the receptacle having a discharge opening therefrom, a filtering screen across said opening, and flange means projecting from the upper end portion of the front wall and serving to deflect wash turbulently motivated toward the top of the receptacle to prevent catching of the wash on the top of the receptacle or entering into the top opening into the receptacle.

7. In a filtering device adapted for use in a laundry machine having a tub, a receptacle having liquid receiving means and a filtering opening, a supporting bracket of truncated wedge-shape provided with dovetail upwardly converging sides, said receptacle having a wall provided with a socket receptive of said bracket, and means along opposite sides of the socket defining undercut grooves complementary to and retainingly engageable with said dovetail sides of the bracket.

8. A filtering device adapted for use in a laundry machine having a tub, said device including a receptacle, a bracket for attachment to the tub and removably engageable by the receptacle, and releasable latch means carried by the bracket and engageable with keeper means on the receptacle to retain the receptacle against unintentional displacement from the bracket.

9. A filtering device for filtering laundry liquid comprising, a receptacle having an upright wall formed with an opening in said wall, a filtering screen extending across said opening, means for receiving laundry liquid in said receptacle including means for directing a flushing stream of said laundry liquid generally horizontally across the inner face of the filtering screen from one side of the opening and into a chamber area of the receptacle beyond the opposite side of said opening, whereby as the flushing stream diminishes in velocity into said chamber space foreign material flushed from the screen tends to sink to the bottom of the receptacle.

10. In combination, a washing machine having a tub formed with upright walls and adapted to contain a supply of laundry liquid therein,

recirculation means including a conduit for delivering recirculated laundry liquid into an upper portion of said tub, and a filtering device positioned inside of said tub, said device comprising

a receptacle having an upright wall formed with an opening in said wall, a filtering screen extending across said opening, means for receiving laundry liquid from said conduit in said receptacle including means for directing a flushing stream of said laundry liquid generally horizontally across the inner face of the filtering screen from one side of the opening and into a chamber area of the receptacle beyond the opposite side of said opening,

and a sump area in the bottom of the receptacle receiving the foreign material which is flushed from the screen and which settles when the flushing stream diminishes in velocity.

11. The invention of claim 10 and further characterized by agitator mechanism in the tub for agitating the contents of the tub and for additionally assisting the flushing of the screen by a back-flow action through the screen.

12. Filtering apparatus adapted for use in a laundry machine having a tub for containing a laundry liquid and further including an agitator mechanism, comprising: a filter device comprising a receptacle including a back wall and a front wall having a screened discharge opening formed therein, means on said back wall for attaching said device in filtering position with said discharge opening submerged, a sump formed in the bottom of the receptacle, means defining a delivery manifold on said receptacle communicating with the interior of the receptacle, and means for directing laundry liquid into the manifold, said manifold having an opening directing a flushing flow of liquid across the screen, whereby filtered material flushed from the screen will settle in the sump.
